Peter A. Barnes

UNITED STATES PATENT OFFICE

PHILIP MEDNICK, OF BROOKLYN, NEW YORK

BRUSH

Application filed April 9, 1932. Serial No. 604,191.

This invention relates to new and useful improvements in brushes, and may appropriately, on account of its unique construction and forceful effect, when applied, be 5 termed a pressure shower-brush.

While a device of this kind may be used for various purposes, a natural application of the same would be in connection with bathing, but the said device may with equal success be used in connection with dishwashing, or other activities, especially when it is 10 slightly modified in shape.

As the construction is comparatively simple, the cost of manufacturing should be 15 proportionately low.

With the above and other objects in view, this invention consists of the novel features of construction, combination and arrangement of parts, hereinafter fully described, 20 claimed and illustrated in the accompanying drawing forming part of this specification, and in which similar characters of reference indicate corresponding parts in all views, and in which;

25 Figure 1 is a bottom view of my device.

Figure 2 is a transverse sectional view, taken on the line 2—2 of Figure 1; while

Figure 3 is a detail view in section.

Referring more particularly to the drawing, 30 10 indicates a wooden member, or block, which in this present invention, or instance, is of an oval shape, with a substantially flat bottom surface, and with provision made at its top, in the form of a recess 11, to engage 35 a handle. The said oval member has in its central area the usual arrangement of bristles 12.

In the said wooden member 10 is formed a 40 circumferentially disposed water-chamber 13; the elongation of the said chamber being near the lower surface of the said brush formed with a set off, or projection, as indicated by the numeral 20, and with sidewise enlarged concave walls 14.

45 The said water-chamber 13 is covered with a plate 15, preferably of metal, and the said plate has been provided with a great number of small oval-shaped perforated areas 16.

On top of the plate 15 is in turn mounted a 50 substantially round gasket 17; the latter has

been formed with apertures 18, tapered in an outward direction, and adapted to register and cooperate with the small oval shaped perforated areas 16, to facilitate the discharge of the water under pressure from the 55 water-chamber 13.

The slightly concave outer portions 14 of the walls of the continuation of the water-chamber will suffice to secure the rubber gasket 17 in place, once the said gasket has been 60 snapped into position.

At one end of the wooden member 10 is inserted a metal tube 19 suitable for attachment thereto of a rubber hose, when water is let 65 into the chamber of the brush during operation.

It is obvious that changes may be made in the form, construction and arrangement of the several parts, as shown, within the scope of the appended claims, without departing 70 from the spirit of the invention, and I do not therefore wish to limit myself to the construction and arrangement shown and described herein.

What I claim as new, and desire to secure 75 by Letters Patent of the United States, is:

1. In a device of the class described, a solid base-member formed with a substantially flat bottom surface, bristles arranged in the center of the said surface, and a circumferential groove formed upon the said base-member, a plate-member having apertures therein and being countersunk in the said groove, a rubber gasket mounted upon the said plate, and holes formed in the said gasket to register with the perforations of the cover-plate.

2. In a device of the class described, a solid base-member, of an oval shape and formed with a substantially flat bottom surface, bristles arranged in the center of the said surface, a circumferential groove made in the said base-member, a plate-member having apertures therein and being countersunk in the said groove, a rubber gasket mounted upon the said plate, and holes formed in the said gasket and tapering outwardly, the said holes being adapted to register with the apertures in the said cover- 100

plate, and an inlet-tube for conveying water to the said groove.

3. In a device of the class described, a solid base-member, of a suitable shape, formed with a substantially flat bottom surface, bristles arranged in the center of the latter, a circumferential chamber formed in the said base-member, the said chamber having concave wall-portions near the bottom surface, a plate-member covering the lower portion of the said chamber, and having little oval areas of perforations therein, a rubber gasket mounted upon the said plate and in the chamber, and being held in place by the concave outer wall-portions, the said gasket having outwardly tapering holes adapted to register with the perforations in the oval areas of the cover-plate.

4. In a device of the class described, a solid base-member, of a suitable shape, formed with a substantially flat bottom surface, bristles arranged in the center of the latter, a circumferential chamber formed in the said base-member, the said chamber having walls, the outer portion of which are concavely shaped and made to receive a rubber gasket, a metal plate centrally disposed with respect to the walls of the said chamber and below the said rubber gasket, the said plate having small oval perforated areas to register with outwardly tapered openings formed in the said gasket, and means for conveying water to the apparatus.

Signed at New York city, in the county of
35 New York, and State of New York, this 29th
day of March A. D. 1932. PHILIP MEDNICK.
